UNITED STATES PATENT OFFICE.

FRANZ KRUCKENBERG, OF HEIDELBERG, GERMANY.

METHOD FOR OVERCOMING GREAT DIFFERENCES OF HEIGHT WITH HIGH-SPEED PASSENGER TRAFFIC.

Application filed January 24, 1925, Serial No. 4,571, and in Germany November 28, 1924.

When it is required to raise a whole railway train to greater elevations, without having recourse to separating the different units, it is performed by means of laying the track in so called serpentines, by means of ramps, viaducts and spiral tunnels, so that the gradients and curves are not too severe for the power of the locomotive. With a high speed railway, however, in which, instead of express-trains a hundred yards in length following each other at long intervals, but single small quick cars, running on a mono rail, at frequent intervals are employed, more simple means can be used. It is possible, e. g., to raise the separate cars by means of lifts, rack-rail or cable-way cars. All these means, however, have the disadvantage of interrupting the continuity of traffic. They interrupt the single switch-less track, the outstanding advantage of the briefly described high speed railway, which makes possible with safety the extremely high speed, with the independence of a complicated time table, that is necessary in the normal railways, and which makes a service of one car per minute possible. If these advantages are to be retained it is impossible to introduce into the track arrangements with other means of operation, which have their own natural period of working, and which have an adverse influence on the whole flow of traffic.

This invention concerns an arrangement, that on the one hand avoids all these disadvantages and on the other hand makes it unnecessary to construct expensive forms of track for overcoming great difference of elevation. This is done by making use of the special quality of the suspension car, which permits it to traverse sharp curves at a considerable speed, without having recourse to great superelevation, in other words that the centrifugal force on the car causes it to swing outward, though it should be noted, that the passengers cannot observe this. This property makes it possible to lay the track in quite sharp spirals or wind it round a tower like the threads of a screw.

In Fig. 1, the case is shown, that the high speed railway must climb up to a plateau 1, which has steep sides, against which are leaned the towers 2 and 3.

Fig. 2 shows a section through a narrow valley, through which flows a stream. The high speed railway has followed this stream

until the position 4, beyond which it cannot go for some reason. Instead of climbing by means of spiral tunnels, viaducts and ramps to the height 5, the track is wound round a tower 6, that is built in the valley, and can be supported on both sides of the valley. Where necessary the construction can be formed as a dam 7, which protects the lower part of the railway against high-water, when the traffic tower can contain a power station, e. g. for supplying the railway with power. The entrance to the tower is through the door 8 and the exit over the bridge 9 and vice versa.

The traffic tower can also be constructed in flat country. In Fig. 3 the case is shown, in which a river, on the shore of which is situated a great town, which is a terminus of the high speed suspension railway, is crossed e. g. by means of a suspension bridge. The track must lie very high over the surface of the river, in order not to interfere with the passage of large vessels. It is impossible to carry the track on a long embankment into the center of the town, owing to the great number of buildings. Therefore on the shore of the river is constructed a tower-like sky-scraper 10, outside or inside of which runs the track 11 in spirals, so that the cars can travel from the bridge 12 to the tunnel 13. In this case also, it is possible to utilize the tower at the same time for other purposes, which is necessary for economical reasons because of the high cost of land. The tower can be built to serve at the same time as business offices, warehouse, or terminal station for any kind of traffic, which can ascend the tower by means of spiral roads or lifts.

For an example in Figs. 4 and 5 is shown a tower in vertical section and horizontal section on A—A, which combines a high speed railway station with a very great station and garage for automobiles and business offices or warehouse. The concentric walls 14 and 15 enclose a space for the up and down tracks 16 and 17 of the spiral railways, also the parallel running entrance and exit roads 18 and 19 of the autos. These roads climb in every quarter revolution the height h (Fig. 4). The different spaces shown in vertical section as rectangles have their use indicated for the sake of clearness; the suspension cars shown by means of circles and the autos with ~~res~~ 119

tangles. Inside the walls 15 at a height equal h platforms 20 are arranged, which serve as garages for the autos. The automobile roads at every quarter turn reach the 5 level of one of these platforms, so that the traffic can reach them conveniently. The difference of level between two roads is 2^h , so that the exits 21 of the roads 19 and the entrances 22 of the roads 18 are diamet- 10 rically opposite (Fig. 15), in such a way that they are spaced from one platform to another at 90° . The arrows show the direction of movement of the cars. In this way we can use the room most economically. In 15 the middle of the tower there are passenger lifts 23, which for the sake of clearness are only shown in plan view. Naturally means for transporting goods vertically can also be incorporated. The in and out going rails 20 are indicated in plan view by means of dotted lines. It can be seen from the lines 16 and 17, that with such a tower the change of direction of the railway may be as sharp as required or in other words the angle 25 d may be chosen at will so that the streets 24 and 25 may be followed.

If there is sufficient ground space, we may build round the cylindrical wall 14 other walls 26, providing space for purpose 30 as required. Because daylight can enter very easily, they would be well suited for business offices, in which case precautions for insulating them from the noise of the cars inside the tower must be taken. These 35 rooms can be so arranged as to be reached by the automobile roads very easily. Similar rooms can also be arranged above the spiral roads. At the same time it is possible to arrange the spiral roads outside the walls 40 of the tower or both inside and outside. In the latter case the rails of both tracks can be laid in the same handed spiral with the tower wall between them, or their planes can cross, so that they are going in right and 45 left handed spirals respectively, a case which must be considered, is if, as in Fig. 6, both rails 16 and 17 approach the tower at the same level, but at a considerable distance apart. Naturally a great number of variations 50 are possible, e. g. the rails of the high speed railway may be entirely outside the tower, further two automobile roads may be arranged outside and four inside, and more roads may be arranged side by side, the number of threads may be increased indefinitely by increasing the diameter of the 55 tower.

Also each direction of rail can have a 60 separate tower and as shown before the inner and outer space may be employed in various ways.

The final determination of the traffic 65 tower in the great town is to serve for the reorganization of high speed passenger traffic in the widest sense of the word and to

bring the great-town problem and the settlements problem nearer to solution.

In order to make this clear, further explanation is necessary.

The crowding together of the business men in the great towns, particularly in the cities cannot be done away with by legislation or instruction, because all forms of life existing in economic societies, animals as well as men, have possessed this instinct for 70 a countless number of years; consider the ants and bees. In this way these forms of life follow the natural impulse to take the line of least resistance, and to avoid all wasted energy, making the total effect of 75 the social organism as great as possible.

Human intentions can be very disastrous if careful use is not made of the existing scientific knowledge and technical ability, or if one popular branch of technique is 80 developed without foresight. The settlement problem has in this way reached a crisis, e. g. the sky-scraper has reached such a size, that traffic is incapable of serving it. Therefore the traffic system must be re- 85 organized. This consists not only in constructing new means of transport, that shall convey passengers quicker, more safely, more conveniently and economically, but these new means of transport must be so suited to the 90 settlement that the people do not only take advantage of these new traffic means if they are fortunate enough, to be inside the 95 settlement, but that all inefficiency in changing the means of transport is reduced to a minimum.

For the new means of transport in question:

1. High speed suspension railway for very high speed and rapid frequency of cars. 105
2. Normal railways of all kinds, specially underground railways and tubes.
3. Intensive transport means, rolling platforms or platforms with feederbands or similar. 110
4. Automobiles.
5. Express-submarines.
6. Air-craft.

All these 6 means of transport have very 115 sharply separated duties.

The high speed suspension railway serves for passenger traffic for great distances over land, underground railways and tubes for the traffic between the city and the suburbs, rolling platform and feederband within the city itself, automobiles for shorter distances over land, express-submarines for sea-voyages; as accelerator for sea-traffic in favourable weather, air-craft.

This may be more specifically illustrated by means of the bird's-eye view of the ideal city in Fig. 7. The circular enclosure is the city itself. It is the center of intensive business life. It contains a great number of 120 sky-scrapers, the various stories of which 130

are connected by lifts. From the street level people reach by means of the feederbands the endless rolling platform 27, which may e. g. be arranged as shown in the drawing 5 and are situated below the streets. All the platforms 27 connect with a single platform 28, which runs round the outside of the whole city. Naturally the platforms 27 and 28 each consist of two endless bands 10 running in opposite directions. By means of the feederband platforms people reach the main-platforms 28 and so the tube-stations 29, the automobile garages, high speed suspension railway stations, express submarine stations and aerodromes.

The purpose of the invention is to construct buildings as stations for the various means of transport, so that the whole traffic system may operate with the maximum efficiency. This purpose is reached as shown in Fig. 7 by means of the towerlike buildings 30, 31^a, 31^b.

Such a traffic tower is similar to those shown in Figs. 4 and 5. The lifts arranged 25 in the center of the whole building run from the cellar to the top-story. On the lowest floor is a feederband station, by means of which people can reach the main-platform 28. Further terminal stations are provided 30 for the high speed suspension railway 33, if it is led to the town by means of tunnels. This terminal station of the high speed suspension railway can also be arranged in the 35 upper stories, if the suspension railway for example must cross a great river, used by great ships, and consequently must enter the town by means of a great bridge 36, supposing the buildings are too numerous. It can also be placed at another part of the 40 main-platforms 28, in order that the tower can serve for overcoming differences of elevation, as shown in the Figs. 4 and 5. Within or immediately adjoining the foot of the tower is the station 34 for the express-submarines. These have nothing else to do 45 with this invention and need only be described as small, quick steamers, which sail at frequent intervals in good weather on the surface and underneath the surface in bad 50 weather. The top-platform 35 is greater than the plan area of the tower, where possible rectangular and turnable. Air-craft with their hangars outside the town or in the upper part of the tower, use this platform 55 for taking up and setting down their passengers, weather permitting. In Fig. 7 the number 30 indicates the above described tower. Numbers 31^a and 31^b are towers without submarine stations. 32 are automobile roads, that converge on the towers.

The manner, in which the traffic is carried out by means of these above described arrangements, will be now explained by a concrete example. Suppose the town shown in 60 Fig. 7 to be New York.

1. A starts with his automobile from his villa at the seashore, drives by the road 32 to the tower 30, garages his auto inside, drops down by a lift to the feederbands and boards the platform 28 for the tower 31^a, travels 70 to Chicago by the high speed suspension railway 33 and returns home in the same manner.

2. B travels by a tube from a suburb of New York and arrives at the station 29, 75 comes by means of the feederbands to the main-platform 28, from which by means of a city-platform 27 he reaches his office, by means of the platforms 27 and 28 and the tower 30; he travels to Boston with the high 80 speed suspension railway.

3. C in the morning leaves his country-house in the neighbourhood of New York in his automobile and travels by the road 32 to the tower 31^b, garages his car and reaches 85 his office by means of the platforms 28 and 27, and leaves the city in the reverse manner, and so on every day.

4. D arrives from Chicago with the high speed suspension railway 33 at the tower 90 31^a, travels by means of the platform 28 to the tower 30 and takes an express-submarine at the station 34 via Azores to Lisbon, from where he travels to Berlin by high speed 95 suspension railway.

5. E will make the same journey. The favourable weather makes air travel safe. He then goes to the tower 30 and takes a lift to the platform 35 and takes an aeroplane to Lisbon via Azores. If the weather between Azores and Lisbon is unfavorable, the aeroplane descends at Azores and E continues his journey by means of the submarines, which sail at frequent intervals.

These examples could be added to indefinitely.

What I claim is:

1. Means for handling traffic in a congested area comprising a continuously travelling railway surrounding such area and provided with stations at suitable intervals, and also located on such railway a tower-like station structure of many stories and having a spirally arranged means for access to any story.

2. A means as described in claim 1 in which the tower-like structures are of such size that on each story is provided space for other purposes such as garages, office rooms, etc.

3. A means as described in claim 1 in which the tower-like structure is provided with elevators extending from the top to the bottom of the structure.

4. A means as described in claim 1 in which the tower-like structure is provided with terminals for high-speed suspension railways.

5. A means as described in claim 1 in which continuously travelling passenger con-

veyors are located within the area and connected to the stations.

6. Means for handling traffic in a congested area comprising a continuously traveling railway surrounding such area and provided with stations at suitable intervals, and also located on such railway a tower-like station structure of many stories and having a spirally arranged means for access to any

story, said tower-like structure being of such size that on each story is provided space for other purposes such as garages, office rooms, etc., said tower-like structure having also elevators extending from the top to the bottom of the structure.

15 In testimony whereof I affix my signature.

FRANZ KRUCKENBERG.
